DESIGN FOR A FOUNTAIN BAG OR THE LIKE

Frank Dabroski, Matawan, N. J.

Application June 15, 1937, Serial No. 69,851

Term of patent 14 years

To all whom it may concern:

Be it known that I, Frank Dabroski, a citizen of the United States and resident of Matawan, in the county of Monmouth and State of New Jersey, have invented a new, original, and ornamental Design for Fountain Bags or the like, of which the following is a specification, reference being had to the accompanying drawing, forming part thereof.

I claim:

The ornamental design for a fountain bag or the like as shown.

FRANK DABROSKI.
